The object of this industrial design is a cap in 4 designs, which is characterized by a harmonious three-dimensional shape, the presence of designer eyelets with an original arrangement on the cap, the implementation of a sewn design of wedges with a rigid curved visor, a semi-oval neckline and a narrow strap on the back and a pattern on the top of six wedges; the cap differs in color, the eyelets in the second and third designs of the cap are made asymmetrically, and in the first and fourth designs—symmetrically.
